UNITED STATES PATENT OFFICE.

ALBERT GOLDSTEIN, OF NEW YORK, N. Y., ASSIGNOR TO INTERNATIONAL ELECTRIC PROTECTION COMPANY, A CORPORATION OF NEW YORK.

ELECTRICAL SIGNALING SYSTEM.

966,824.

Specification of Letters Patent. Patented Aug. 9, 1910.

Application filed March 9, 1910. Serial No. 548,258.

To all whom it may concern:

Be it known that I, ALBERT GOLDSTEIN, a citizen of the United States, residing at New York, in the county of New York and State of New York, have invented a certain new and useful Improvement in Electrical Signaling Systems, of which the following is a specification.

The invention is a central energy electrical 10 signaling system, in which successive code signals may continue to be sent from a plurality of transmitters, notwithstanding an abnormal disturbance—such as a break—in the electrical conditions of the circuit, and 15 in which the transmitters are timed and their operation rendered successive by electrical means: the said means here comprising thermostatic switches heated and so controlled by the current on the circuit.

20 In the accompanying drawing—Figure 1 is an electrical diagram, showing my invention by conventional symbols. Fig. 2 is a side elevation of one of the thermostatic switches.

25 Similar numbers and letters of reference indicate like parts.

Located at the receiving station is a source A of current, here shown as a split battery, which is grounded at G. At three distant 30 stations are the transmitters T, T', T'', the line conductor between the stations being shown at 1 and 25. At the receiving station are the magnets D, E respectively interposed in line conductors 1, 25 and each controlling 35 a local circuit from battery L to the glow lamps P, Q, so that when either magnet vibrates its switch lever d or e to open or close its local circuit, the signals will be translated by said lamps.

40 The metallic circuit proceeds as follows: From source A to magnet D; line wire 1, to transmitter T and therein to contact 2, heat switch arm S², wire 3, switch n³, contact 4, wire 5, switch o, contact 6, wire 7, heat 45 switch arm S³, contact 8 and thence by wire 9, to transmitter T', and therein to contact 10, heat switch arm S³, wire 11, switch n⁷, contact 12, wire 13, switch o', contact 14, wire 15, heat switch arm S⁶, contact 16 and 50 thence by wire 17 to transmitter T'', and therein to contact 18, heat switch arm S⁶, wire 19, switch n¹¹, contact 20, wire 21, switch o², contact 22, wire 23, heat switch arm S⁶, contact 24 to line wire 25, magnet 55 E to source A.

The transmitter T is constructed and operates as follows: When either or both of the magnets W or W' are energized, the hinged armature w is attracted, thus releasing the pallet tail t of the usual clock-work mechanism which rotates code wheel M, and withdrawing the detent h from the notch in the rim of the winding drum i of said mechanism. As soon as the winding drum has completed one revolution synchronously 60 with code wheel M, the detent h again engages with said notch. The same result is produced through magnets W², W³ of transmitter T', and through magnets W⁴, W⁶ of transmitter T''. 65

In order that the transmitters T, T', T'' may send in their signals successively, no matter in what order they may be operated, or whether they be operated simultaneously or otherwise, the following construction is 70 provided: Magnet W is in a shunt having terminals at contact point 8, and junction x. Magnet W' is in a shunt having terminals at contact point 2, and junction y. Under normal conditions, as already described, contacts 8 and 2 are closed and magnets W and W' are short-circuited, and accordingly de- 75 energized. The hinged armature w then being retracted, the pallet tail t is locked, and the detent h engages in the notch of 80 winding drum i. When, however, the lever o is depressed, circuit being opened at point 6 proceeds as follows: from wire 1 to contact 2, heat switch arm S², coil on said arm, wire 28, wire 29, contact 30, switch n', contact 31, switch n², wire 32, coil of heat switch S³, heat switch arm S³, contact 8 and wire 9, as before. The coils on heat switch arms S², S³ now become heated by the current, 85 thus producing unequal expansion of the 90 thermostatic arms within them, and causing said arms to bend sufficiently to open circuit at contacts 2 and 8. This enables current to pass to the magnet shunts, thus energizing magnets W, W' and, causing in the 95 manner already described, the release of code wheel M which, rotating in the usual 100 way, sends signals over the line.

It is to be observed that code wheel M sends impulses by intermittently closing the 105 circuit, and under normal operating conditions, this circuit is closed to ground G'.

After magnets W, W' have been energized, as above described, the circuit proceeds as follows: from wire 1, through mag- 110

net W' to junction y, coil of heat switch S², wire 28, wire 29, contact 30, switch n', contact 31, switch n², wire 32, coil of heat switch S³, junction x, magnet W to wire 9.

5 On the shaft of wheel M is a cam N having an insulating ring on its periphery. On this ring the bent over end of switch arm n bears while said wheel and cam are in rotation. In this way the arm n is raised together 10 with arms n', n², n³, which are connected to arm n by intermediate bars of insulating material, thus opening circuit at contacts 30, 31 and 4, and closing circuit to ground G' at contact 34. When this is done the 15 code wheel M controls the circuit to ground G', by operating switch arms m, m', connected by a bar of insulating material, to open and close contacts 35 and 36 which, by wire 37, contact 34 and switch n, connect to 20 ground G'.

In order to prevent a premature restoring of switch o to its original position, closing a short-circuit by wires 5 and 7 around the transmitter T, the switch n³ is provided, 25 which opens contact 4 in series with wire 5.

The construction of transmitters T' and T² is the same as that of transmitter T, with 30 which they are connected in series in the metallic circuit. The heat switches S², S³ of transmitters T, S⁵, S⁶ of transmitter T' and S⁸, S⁹ of transmitter T², are to be constructed so that the switch arms in each transmitter will operate at a different time—as for example, first, in transmitter T, second, in transmitter T' and third, in transmitter T²—when their coils are heated simultaneously. This may be accomplished 35 in a variety of known ways, as by proportioning the resistances of the coils, or the cross sectional area or by selection of materials of the thermostatic elements, or by varying the normal pressures of the contacts—as 2 and 8—in the several transmitters against the arms.

40 Assume now that the transmitter T be operated, the transmitters T', T² will not operate, because the low resistance circuit to ground G' is only closed momentarily by switch m, and current then does not pass for a long enough period of time to the coils 45 of the heat switches of transmitters T', T² to operate said switches.

So far I have described the operation of the system on normal circuit. I will now 50 assume that a disturbance occurs in the electrical conditions on the line, say a break. If said break, say at Z, occurs on wire 1, then there will be two leads formed from the source A: namely (1) to magnet D, wire 1 to break; and (2) to magnet E, wire 25, contact 24, heat switch arm S⁹, wire 23, contact 22, switch o², wire 21, contact 20, switch n¹¹, wire 19, heat switch arm S⁸, contact 18, by wire 17 to transmitter T' and 55 therein contact 16, switch arm S⁶, wire 15,

contact 14, switch o', wire 13, contact 12, switch n⁷, wire 11, heat switch arm S⁵, contact 10, by wire 9 to transmitter T and therein contact 8, switch arm S³, wire 7, contact 6, switch arm o, wire 5, contact 4, 70 switch n³, wire 3, heat switch arm S², contact 2, and wire 1 to break. If, on the other hand, the break occurs in wire 25, say at Z', again there will be two leads formed from source A: namely (1) to magnet D, wire 1 75 and so through the transmitters T, T', T² but in the reverse direction to the second lead above described, to break Z'; and (2) to magnet E, wire 25 to break Z'. It will be obvious that in either case, in order to 80 operate any one of the transmitters, a ground must be provided at that transmitter. I will assume that the break is in wire 25 at Z', and that it is desired to 85 operate transmitter T. The switch o is opened at contact 6, as already described, but because of the break nothing can happen unless a current path to ground is established. This I do by the following means. Connected to switch o by a bar of 90 insulating material is a switch p which connects with wire 1 by way of wire 45, switch n', contact 30, wire 29, wire 28, coil of heat switch, heat switch arm S², and contact 2. In the path of switch p is a contact 95 47 which connects with ground G' through the coil of heat switch S⁴. Hence when switch o opens circuit at contact 6, it closes circuit at 47 and so connects wire 1 with ground.

The coil of heat switch S⁴ is made of very high resistance as compared to the coil of heat switch S²—say 20,000 ohms to 20 ohms—so that although the two coils are in series, S⁴ only is heated. When heated, the 100 thermostatic arm inclosed in said coil establishes contact with point 44 which is connected with the coil of S⁴. This short-circuits the greater part of the resistance offered by said coil, so that the increased 105 current now passing through the coil of S² is sufficient to heat the switch arm therein and cause said arm to open the shunt around magnet W' at point 2, thus energizing said magnet and setting the code wheel M in 110 operation in the manner already described. The reason for making the coil of heat switch S⁴ of very high resistance is to prevent signals sent from the other transmitters from being cut off from the receiving station, as would happen if the ground provided for transmitter T were of low resistance.

I claim:

1. The combination of a source of current, a metallic circuit, a plurality of transmitters in series therein, a plurality of translating devices controlled by said transmitters, means operated by an abnormal disturbance of electrical conditions on the 125 130

circuit for establishing two current leads, one of said leads including a translating device and two or more transmitters, and means for controlling said included transmitters to operate successively.

2. The combination of a source of current, a metallic circuit, a plurality of transmitters in series therein, a plurality of translating devices controlled by said transmitters, means operated by an abnormal disturbance of electrical conditions on the circuit for establishing two current leads, one of said leads including a translating device and two or more transmitters, means for controlling said included transmitters to operate successively, and means for preventing mutual interference of the current im-

pulses respectively sent by said transmitters.

3. The combination of a source of current, 20 a metallic circuit, a plurality of transmitters in series therein, thermostatic circuit closers associated with each transmitter and controlling the same, the said thermostatic circuit closers being relatively timed to 25 cause said transmitters to operate successively, and translating devices controlled by said transmitters.

In testimony whereof I have affixed my signature in presence of two witnesses.

ALBERT GOLDSTEIN.

Witnesses:

GERTRUDE T. PORTER,
MAY T. McGARRY.
